UNITED STATES PATENT OFFICE

2,602,563

TUB CONSTRUCTION FOR WASHING
MACHINES AND THE LIKE

Edward G. Lipski, Bristol, Pa., assignor to General Electric Company, a corporation of New York

Application May 26, 1950, Serial No. 164,423

6 Claims. (Cl. 220—10)

1

This invention relates to an improved tub construction for washing machines and the like in which the tub is mounted within an external casing having a top portion which, on occasion, it may be necessary to remove. In particular, my invention relates to an improved tub rim which seals against the underside of the casing top and provides means for releasably securing the casing top in its home position.

The application of my invention may best be exemplified in clothes washing machines of the centrifugal extraction type. In such machines the clothes are dried by rapidly spinning a receptacle—a "basket"—rotatably mounted within a tub which collects the water discharging from the basket. In certain types of such washing machines the basket is also the receptacle within which the clothes are mechanically agitated for washing, and the basket is imperforate except for a line of openings near the top thereof through which wash water overflows to the tub and through which the centrifugally extracted wash water leaves the clothes. In such constructions the upper rim of the basket may be only a few inches below the upper rim of the tub and the casing cover and it is important to prevent the water from splashing over the edge of the basket or tub and falling into the space between the tub wall and the outer casing wall.

It is an object of this invention to provide a tub construction having an easily applied, flexible rim portion which seals against the upper edge of the tub and extends upwardly into continuous peripheral engagement with the underside of the casing top.

A further object of the invention is to provide a washing machine tub having an upper flexible rim portion which seats resiliently and in a continuous line with the underside of the wall of a tub cover structure to minimize the escape of liquid from the tub.

It is still another object of the invention to provide a washing machine tub construction having a flexible rim as aforesaid and in addition a plurality of members over which a marginal wall of a tub cover structure may be forced so as to be releasably held in position with respect to the tub.

It is still another object of the invention to provide a tub construction which affords a simplified means for mounting the tub and the casing cover on an outer supporting framework of a washing machine or the like.

In a presently preferred form of my invention

as hereinafter more fully described, I may fabricate the tub body sidewalls from sheet metal and affix to the upper edge thereof a rubber or equivalent rim member characterized by a heavy body engaging with said sidewalls and having a continuous substantially frusto-conical lip rising therefrom. At suitable intervals about the rim—at 90 degree spacing when the tub is to be enclosed in a supporting structure of rectangular shape—I provide flange-like extensions which project beyond the side margins of the supporting structure. It is advantageous to make said extensions integral with the tub rim member in that they then provide secure areas at which screws or the like may pass through the rim member and an upper edge flange of the tub for attachment of the latter to the supporting means. The extensions also provide for locking a cover structure removably in position by snapping or forcing a rolled edge portion of the cover over the edge portions of the extensions. Such an arrangement makes it unnecessary to provide additional fastening means for the cover and thus simplifies the initial assembly of the machine and the removal of the cover for inspection or repair of structures as may normally be concealed by said cover. The upward projection of the frusto-conical lip is such that when the cover is placed in home position the flexible lip is distorted downwardly by the undersurface of the cover and forms therewith a continuous line of engagement which is effective to prevent water which may splash out of the tub from passing to the outer wall of the tub or the like.

35. A similar rim member construction may be provided where the tub sidewalls are themselves made of rubber. In such construction the rim member and the extension members may be molded as an integral part of the tub sidewall.

40. These and other features and advantages will be better understood from a description of the embodiment shown in the accompanying drawing, in which Fig. 1 is a top plan view of a washing machine casing of which the tub embodies the present invention, certain portions of the cover and casing being broken away to illustrate underlying structure; Fig. 2 is a side sectional elevation taken on line 2—2 of Fig. 1; and Fig. 3 is a side sectional elevation taken on line 3—3 of Fig. 1, better to illustrate the method of securing the respective elements.

The top plan view of a domestic washing machine which I have chosen to illustrate a typical use of my invention shows, see Fig. 1, a substan-

tially rectangular casing 1 having an inwardly extending wall or flange 2 at the top of the casing. The inner edges of said wall portions are shaped so as collectively to provide a top wall opening 3 of suitable shape. Within said opening is suspended a tub 4 which has flange means 5 forming the upper margin of an inwardly extending bead 6. It is preferable that the wall or walls 2 of the casing 1 provide a substantially continuous shoulder or step on which the tub flange 5 may rest. It should be understood that the circular opening and circular tub are by way of example only.

The present invention contemplates associating with said tub a resilient structure or structures which provide means for releasably retaining a cover 7 in position on the casing and for sealingly engaging the underside of said casing to prevent the contents of the tub from splashing over the tub rim and dropping into the space between the tub and casing. As is evident in Fig. 2, the cover 7 comprises a cover for the tub, although essentially it is the top or cover wall of the casing. A removable lid 7a affords access to the tub for loading and unloading the same. For such securing and sealing, I provide an annular member 8 of rubber or the like having a relatively thick-walled body 9 downwardly extending from which is a continuous lip 10. By suitably sizing the member 8 relative to the tub, the lip will envelop the tub bead 6 relatively tightly throughout the periphery thereof upon positioning the body 9. Adhesives or similar bonding materials are not normally required, or desirable. At a plurality of areas around the periphery of the tub—for example, four areas in a rectangular casing construction—the member 8 is provided with snubber members 11 which extend outwardly over the flange 5, as indicated in Fig. 3. The outermost edges of said members are parallel with the sidewalls of the casing and are preferably rounded as clearly appears in Fig. 3. The length of said members is such as to provide for the passage of a screw or equivalent fastening 12 through the members 11 and the flanges 5 and 2 of the casing and tub. It is thus possible in the rectangular casing illustrated to secure the rim member 8 and the tub 4 to the casing by at least eight fastenings. Extending upwardly from the body 9 is a continuous frusto-conical lip 14 having a relatively thick moderately stiff base wall portion and a substantially thinner, flexible, outer edge portion.

It has in the past been the practice to secure the casing cover 7 to the body of the casing by screws or the like. The snubbing members provided herein secure the cover removably in position on the casing. To this end I provide the edge of the cover structure with a re-entrant bead 15 shaped to fit snugly about the rounded outer edge of the snubbers 11 as shown in Fig. 3. By soaping or otherwise lubricating said snubbers the casing may be forcibly snapped thereover and will be held securely in position thereon. In this same operational step the underwall of the casing cover engages the outer edge portion of the lip 14 which, as is shown in Fig. 3, has a relaxed length indicated in dotted line. The upper edge of the lip 14 is thus deflected downwardly so as to seat against the cover throughout the periphery of said lip. The area of said engagement is moderate but is nevertheless effective to prevent water which may splash out of the tub from passing over the upper edge of the lip 14 and then to trickle or drip down the inside wall of the casing. The relatively

heavy base portion of the lip 14 provides sufficient reactive force to maintain the engagement between the end of the lip 14 and the casing cover 7. The inward slope of the lip guards against leakage resulting from masses of water striking forcefully thereagainst.

It will thus be seen that I have provided a tub rim construction which provides means for securing a cover member in home position and for preventing the escape of water from the tub to the inside wall portion of the casing. An advantage of substantial practical importance which derives from the use of my invention resides in the fact that there are no externally apparent means of securing the casing cover on the casing. The amateur mechanic is thus at a loss to understand the method of attachment and removal of the casing, and is thereby discouraged from attempting to remove the casing so as to get access to the various valves and control elements normally mounted within the casing or immediately beneath the casing cover. Nevertheless, to the serviceman or other person qualified to inspect or repair the apparatus, the casing cover is easily removed and replaced.

While I have shown a particular embodiment of my invention, it will be understood, of course, that I do not wish to be limited thereto since many modifications may be made; and I therefore contemplate by the appended claims to cover any such modifications as fall within the true spirit and scope of my invention.

What I claim as new and desire to secure by Letters Patent of the United States is:

- 35 1. In combination, a supporting structure having an inwardly extending upper flange, a receptacle having an outwardly extending rim engaging said flange for the securement of said receptacle thereto, the rim of said receptacle, further, having an inwardly extending, continuous bead, cover means for said receptacle, means for providing a seal between said cover means and said receptacle including a resilient body member snugly engaging with the said bead portion of said receptacle and having flexible lip means extending angularly upwardly therefrom to bear resiliently against the under surface of said cover means, and means for removably securing said cover means relative to said receptacle, including resilient members integral with said body member and extending radially outwardly therefrom in surface contact with said rim and having outer edge portions overhanging said flange, a lower marginal edge of said cover means having a re-entrant curvature for engagement with said overhanging edge portions, and means passing through said resilient member and said receptacle rim to secure the same jointly to said upper flange.
- 40 2. In combination, a supporting structure having an inwardly extending upper flange, a receptacle having an outwardly extending rim engaging said flange for the securement of said receptacle thereby, the rim of said receptacle, further, having an inwardly extending, continuous bead, cover means for said receptacle, means for providing a seal between said cover means and said receptacle including a resilient body member integral with said body member and extending radially outwardly therefrom in surface contact with said rim and having outer edge portions overhanging said flange, a lower marginal edge of said cover means having a re-entrant curvature for engagement with said overhanging edge portions, and means passing through said resilient member and said receptacle rim to secure the same jointly to said upper flange.
- 45 3. In combination, a supporting structure having an inwardly extending upper flange, a receptacle having an outwardly extending rim engaging said flange for the securement of said receptacle thereby, the rim of said receptacle, further, having an inwardly extending, continuous bead, cover means for said receptacle, means for providing a seal between said cover means and said receptacle including a resilient body member integral with said body member and extending radially outwardly therefrom in surface contact with said rim and having outer edge portions overhanging said flange, a lower marginal edge of said cover means having a re-entrant curvature for engagement with said overhanging edge portions, and means passing through said resilient member and said receptacle rim to secure the same jointly to said upper flange.
- 50 4. In combination, a supporting structure having an inwardly extending upper flange, a receptacle having an outwardly extending rim engaging said flange for the securement of said receptacle thereby, the rim of said receptacle, further, having an inwardly extending, continuous bead, cover means for said receptacle, means for providing a seal between said cover means and said receptacle including a resilient body member integral with said body member and extending radially outwardly therefrom in surface contact with said rim and having outer edge portions overhanging said flange, a lower marginal edge of said cover means having a re-entrant curvature for engagement with said overhanging edge portions, and means passing through said resilient member and said receptacle rim to secure the same jointly to said upper flange.
- 55 5. In combination, a supporting structure having an inwardly extending upper flange, a receptacle having an outwardly extending rim engaging said flange for the securement of said receptacle thereby, the rim of said receptacle, further, having an inwardly extending, continuous bead, cover means for said receptacle, means for providing a seal between said cover means and said receptacle including a resilient body member integral with said body member and extending radially outwardly therefrom in surface contact with said rim and having outer edge portions overhanging said flange, a lower marginal edge of said cover means having a re-entrant curvature for engagement with said overhanging edge portions, and means passing through said resilient member and said receptacle rim to secure the same jointly to said upper flange.
- 60 6. In combination, a supporting structure having an inwardly extending upper flange, a receptacle having an outwardly extending rim engaging said flange for the securement of said receptacle thereby, the rim of said receptacle, further, having an inwardly extending, continuous bead, cover means for said receptacle, means for providing a seal between said cover means and said receptacle including a resilient body member integral with said body member and extending radially outwardly therefrom in surface contact with said rim and having outer edge portions overhanging said flange, a lower marginal edge of said cover means having a re-entrant curvature for engagement with said overhanging edge portions, and means passing through said resilient member and said receptacle rim to secure the same jointly to said upper flange.
- 65 7. In combination, a supporting structure having an inwardly extending upper flange, a receptacle having an outwardly extending rim engaging said flange for the securement of said receptacle thereby, the rim of said receptacle, further, having an inwardly extending, continuous bead, cover means for said receptacle, means for providing a seal between said cover means and said receptacle including a resilient body member integral with said body member and extending radially outwardly therefrom in surface contact with said rim and having outer edge portions overhanging said flange, a lower marginal edge of said cover means having a re-entrant curvature for engagement with said overhanging edge portions, and means passing through said resilient member and said receptacle rim to secure the same jointly to said upper flange.
- 70 8. In combination, a supporting structure having an inwardly extending upper flange, a receptacle having an outwardly extending rim engaging said flange for the securement of said receptacle thereby, the rim of said receptacle, further, having an inwardly extending, continuous bead, cover means for said receptacle, means for providing a seal between said cover means and said receptacle including a resilient body member integral with said body member and extending radially outwardly therefrom in surface contact with said rim and having outer edge portions overhanging said flange, a lower marginal edge of said cover means having a re-entrant curvature for engagement with said overhanging edge portions, and means passing through said resilient member and said receptacle rim to secure the same jointly to said upper flange.
- 75 9. In combination, a supporting structure having an inwardly extending upper flange, a receptacle having an outwardly extending rim engaging said flange for the securement of said receptacle thereby, the rim of said receptacle, further, having an inwardly extending, continuous bead, cover means for said receptacle, means for providing a seal between said cover means and said receptacle including a resilient body member integral with said body member and extending radially outwardly therefrom in surface contact with said rim and having outer edge portions overhanging said flange, a lower marginal edge of said cover means having a re-entrant curvature for engagement with said overhanging edge portions, and means passing through said resilient member and said receptacle rim to secure the same jointly to said upper flange.

to said flange and having outer edge portions overhanging the same, a lower marginal edge portion of said cover means having a re-entrant curvature for releasable engagement with said overhanging edge portions.

3. In combination, a supporting structure having an inwardly extending upper flange, a receptacle having an outwardly extending rim means engaging said flange for the support of said receptacle thereby, cover means for said receptacle, means for providing a seal between said cover means and said receptacle including a resilient body member expanding radially into engagement with the rim portion of said receptacle and having flexible lip means extending upwardly therefrom to bear resiliently against the under surface of said cover, and means for removably securing said cover relative to said receptacle, including resilient members fixed to said flange and having outer edge portions overhanging the same, lower marginal edge portions of said cover means having a re-entrant curvature for releasable engagement with said overhanging edge portions.

4. In combination, a receptacle, a cover for said receptacle, means providing a seal between said receptacle and said cover including a flexible body member in engagement with an upper edge portion of said receptacle and flexible lip means extending upwardly and inwardly from said body member throughout the periphery thereof to bear resiliently against the underside of said cover, and flexible means integral with said body member and extending outwardly therefrom below said lip member for engagement with said cover, the lower marginal edge portion of said cover having a re-entrant curvature for releasable engagement with said outwardly extending flexible means.

5. In combination, a supporting framework 40

having an inwardly extending upper marginal portion, a receptacle having flange means engaging said inwardly extending portion for securement thereto, a cover for said receptacle, means providing a seal between said receptacle and said cover, and flexible means formed integrally with said seal means extending outwardly therefrom beyond said receptacle flange means, said cover having a re-entrant curvature on its lower marginal edge for engagement with said flexible means to retain said cover releasably on said receptacle.

6. In combination, a receptacle having an upper rim extending outwardly therefrom, a cover for said receptacle, flexible members extending radially outwardly from said rim, said cover having a marginal wall configurated for releasable engagement with said flexible members for securement of said cover to said receptacle, and means for providing a seal between said cover and said receptacle, said means including a resilient body member in surface contact with said rim and having a flexible lip extending around its periphery and projecting upwardly and inwardly from said body member to a height sufficient to engage the underside of said cover in sealing relationship therewith.

EDWARD G. LIPSKI.
